RADIO APPARATUS

Arthur M. Trogner, Maplewood, N. J., assignor to
Wired Radio, Inc., New York, N. Y., a corpora-
tion of Delaware

Application August 19, 1931. Serial No. 558,045

3 Claims. (Cl. 179—2.5)

My invention pertains in general to radio receiving means and specifically relates to radio receiving apparatus for receiving either wired radio or space radio signals.

5 One of the objects of my invention consists in providing a radio receiving system in which commonly controlled means are provided for receiving either wired radio or space radio signals.

Another object comprises providing radio apparatus in which common variable condensers and an associated indicating dial are provided for co-operation with different circuits for the reception of either wired radio or space radio signals.

15 A further object consists in providing radio apparatus having variable condensers adjustable by contiguous increments for space radio reception and movable in predetermined steps for wired radio reception.

20 I accomplish these and other desirable objects in a novel radio apparatus having variable condensers common to wired radio and space radio reception circuits mechanically connected with an indicating dial provided with an aperture 25 mask movable under control of a selection switch for either wired radio or space radio reception.

In the drawings which accompany and form a part of this specification and in which like reference numerals designate corresponding parts 30 throughout:

Fig. 1 is a side elevation and partially sectioned view of one embodiment of the radio apparatus of my invention;

Fig. 2 is a fragmentary transverse sectional view along the line 2—2 of Fig. 1;

Fig. 3 is a fragmentary transverse sectional view along the line 3—3 of Fig. 1.

Fig. 4 is a fragmentary sectional view along the line 4—4 of Fig. 1; and

40 Fig. 5 is a diagrammatic representation of the electrical circuit employed in the present embodiment of my invention.

My invention is directed to providing a radio receiving system having common variable condensers and an associated indicating dial for receiving carrier frequency signals or space radio signals over different circuit paths. In accordance with my system these variable condensers are adjustable by contiguous increments for 45 space radio reception and are adjustable in predetermined steps for wired radio reception. Referring to the drawings in detail and particularly to Figs. 1 and 3, I provide a base member 1 having a mounting structure 2 secured thereto. A 50 plurality of groups of variable condenser stator

plates 3, 4, 5, and 6 are mounted upon insulating members within a frame member 11 mounted on top of the mounting structure 2. A plurality of groups of variable condenser rotor plates 7, 8, 9, and 10 are mounted on a shaft 13 for engagement with their respective groups of stator plates 3, 4, 5, and 6. The shaft 13 is journaled between two extremities of the frame member 11 and extends through an aperture in a panel 14 secured to the base 1. A knob 15 is secured to the end of the shaft 13 to permit manual rotation of the groups of rotor plates 7, 8, 9, and 10 with respect to their associated stator plates. In accordance with my invention a dial 17 is rigidly mounted upon the shaft 13. As shown in Fig. 2, this dial 70 17 is provided with a plurality of radial lines and corresponding numbers for indicating the relative position of the variable condenser rotor plates and stator plates as well as the designations "A", "B", and "C" for indicating predetermined positions of the variable condenser rotor plates with respect to the stator plates.

A masking plate 20 is mounted on the shaft 13 in a manner such that it is free to rotate thereon. This masking plate 20 is provided with two apertures 21 and 22 angularly displaced from one another, as shown in Fig. 2. The aperture 21 is adapted to register with the space radio radial designations on the dial 17, while the aperture 22 is adapted to register with the wired 85 radio designations "A", "B", and "C" on the dial 17. The apertures 21 and 22 may be brought into register, one at a time, with a larger aperture 23 in the front panel 14.

A knob 24 is rigidly mounted upon a shaft 26 90 which is rotatably mounted in a bearing member in the mounting structure 2. The shaft 26 carries an arm 27 pivotally coupled to the masking plate 20 by a pivot 28. The shaft 26 also carries a clicker member 29 having two indents therein 95 for receiving a resilient detent member 30 secured to the mounting structure 2 by a lug 31. The indents in the clicker member 29 correspond to the two different positions of the masking plate 20 in which the apertures 21 and 22 are respectively in register with the aperture 23.

A clicker disk 33 is rigidly secured to the shaft 13 and is provided with three peripheral indents 34 corresponding to the three angular positions of the dial 17 in which the designations "A", "B", and "C" are individually in register with the aperture 23 of panel 4. A detent member 35 is pivotally mounted upon the frame member 11 for engagement with the indents 34 of the clicker disk 33. The member 35 is provided with a 110

flange 36 upon which a roller 37 rides. The roller 37 is pivotally mounted on an arm 38 rigidly secured to the shaft 26 adjacent the hub of the arm 27. A compression spring 39 is mounted between a pillar 40 and the member 35 whereby the member 35 is normally held in peripheral engagement with the clicker disk 33.

A link member 41 is pivotally connected at its center portion with an extended part of the arm 38. The extremities of the link member 41 are pivotally connected to two switch arms 42 and 43 which are pivoted upon the mounting structure 2. The arms 42 and 43 are each secured to an insulating bar 45, (see Fig. 3) which carries a plurality of switch contacting knives. These contacting knives are indicated in Fig. 5 as contacting knives 46, 47, 48, and 49 which are mounted upon the insulating bar 45 of the switch arm 42, while the switch contacting knives 50, 51, 52, and 53 are mounted on the insulating bar 45 mounted on the switch arm 43. These switch contacting knives engage with respectively disposed contacting clips 54 which are secured to insulating strips 55 mounted on the frame member 11. The switch contacting knives 47, 48, and 49 and their respective terminal clips mounted on the side of the frame member 11 adjacent the contacting knife 46 are not shown in the drawings but exactly correspond in structure to the corresponding elements on the other side of the frame member 11 as shown in Fig. 1.

The electrical organization of my invention will now be considered. Referring to Fig. 5, a space radio energy collecting system comprising an antenna 60 and ground 61 are connected through an inductance 62 electromagnetically coupled to an inductance 63. The inductance 63 is connected in series with an inductance 64, electromagnetically coupled to an inductance 65 and through switch element 50 with the variable condenser plates 3 and 7. The inductance 65 is connected in series with an inductance 66, electromagnetically coupled to an inductance 67, and through switch element 51 with condenser plates 4 and 8, while the inductance 67 is connected in series with an inductance 68, electromagnetically coupled to an inductance 69, and through switch element 52 with condenser plates 5 and 9. The inductance 69 is connected through switch element 53 to the condenser plates 6 and 10 and a resistance 70. The inductances 62 to 69 in combination with the condensers 3—7, 4—8, 5—9, and 6—10 form a plurality of inductively coupled meshes comprising a band pass filter having a terminating impedance of a proper value in the resistance 70. The output of this filter is connected as shown in Fig. 5 to the control electrode and cathode of a space discharge radio frequency amplifier tube 72. The output or anode to cathode of circuit of the space discharge tube 72 includes the primary winding of a radio frequency transformer 75. The secondary winding of the radio frequency transformer 75 is connected to the cathode and through a condenser and grid leak 76 to the control electrode of a space discharge detector tube 73. The output or anode to cathode circuit of the space discharge tube 73 includes the primary of an audio frequency transformer 77 having the secondary winding thereof connected between the control electrode and cathode of a space discharge audio frequency amplifier tube 74. The output or anode to cathode circuit of the space discharge tube 74 includes the primary winding of an audio frequency transformer 78 having the

secondary winding thereof connected to a suitable translating device such as a loud speaker 79.

In accordance with my invention, power lines 80 carrying commercial alternating current and carrier frequency energy are coupled through condensers 81 and 82 to an input inductance 83. The carrier frequency energy transmitted over the power lines 80 comprises several programs simultaneously transmitted at discrete carrier frequencies. The commercial alternating current conveyed by the power lines 80 may be used for supplying operating voltage by means of a rectifier system to the space discharge tubes 72, 73, and 74 in lieu of the batteries which are shown in Fig. 5 for the sake of simplicity.

An inductance 84, electromagnetically coupled to an inductance 85, is connected in series with the inductance 83 and through switch element 46 to the condenser plates 3 co-operating with condenser plates 7. An inductance 86, electromagnetically coupled to an inductance 87, is connected in series with the inductance 85 and through switch element 47 with condenser plates 4 co-operating with condenser plates 8. An inductance 88, electromagnetically coupled to an inductance 89, is connected in series with the inductance 87 and through switch element 48 with condenser plates 5 co-operating with condenser plates 9. The inductance 89 is connected in series with a resistance 90 and through the switch element 49 with condenser plates 6 co-operating with the condenser plates 10. The inductances 83 to 89, in combination with the condensers 3—7, 4—8, 5—9, and 6—10, form a plurality of inductively coupled meshes comprising a band pass filter having a terminating impedance of a proper value in the resistance 90. This last described filter system is adapted to select carrier frequency energy at one frequency transmitted over power lines 80. The output of this filter is connected to the control electrode and cathode of the space discharge radio frequency amplifier tube 72.

Referring to Figs. 1 and 3, space discharge tubes 72, 73, and 74 are mounted upon the rear portion of the mounting structure 2. The inductances 62 to 69 and the inductances 83 to 89 are mounted within shielding compartments 91 within the mounting structure 2.

In the operation of my radio apparatus for reception of space radio signals, the electrical circuits will be in a condition as depicted in Fig. 5. That is, the switch blades 50 to 53 will be closed, while the switch blades 46 to 49 will be open. This is mechanically accomplished by manual movement of knob 24 shown in Fig. 1 whereby the link member 41 is longitudinally moved to cause the switch arms 42 and 43 to move the switch blades referred to. At the same time, the arm 27 will have moved the masking plate 20 into a position such that the aperture 21 is in register with the radial designations on the dial 17 for indicating, at the aperture 23, the relative position of the rotor plates 7 to 10 with reference to the rotor plates 3 to 6 inclusive. In this space radio reception position, the member 38 will also be in a position as depicted in Fig. 4 in which the roller 37 has depressed the flange 36 to cause the detent member 35 to be disengaged from the periphery of the clicker disk 33. The knob 15 can now be manually moved by contiguous increments for any desired position of the condenser rotor plates 7, 8, 9, and 10 whose position will be indicated by the indicia on dial 150

17 at the aperture 23 as appearing through the smaller aperture 21 in the masking plate 20.

Referring to Fig. 5, the space radio signals will be received over the space radio energy collecting system 60—61 and the selective filter system connected therewith. The knob 15 may be manually rotated for proper adjustment of the condenser rotor plates 7, 8, 9, and 10 whereby the selective filter system coupled to the space radio energy collecting system 60—61 is rendered responsive to any desired space radio program at any particular frequency. The space radio signals are amplified by the radio frequency amplifier tube 72 and detected by the detector tube 73 for reproduction over the audio frequency system including space discharge tube 74 and translating device 79. It is an especial feature of my invention that, for space radio operation, the knob 15 may be moved by contiguous increments for adjustment of the variable condensers for selection of a great many different frequencies which may be closely adjacent on the frequency spectrum.

For the operation of my radio apparatus for the reception of wired radio signals, the knob 15 is manually moved into a position such that the aperture 22 is in register with the wired radio indications "A", "B", and "C" on the dial 17 at the aperture 23 in panel 14. In this position of the masking plate 20, the switch arms 42 and 43 will have been moved into a position such that the switches 46, 47, 48, and 49 will be closed and the switches 50, 51, 52, and 53 will be open. At the same time, the arm 38 will have moved the roller 37 into a position such that the flange 36 will be released whereby spring 39 will force the detent member 35 into peripheral engagement with the clicker disk 33. The clicker disk will then have a tendency to be arrested at the angular positions in which the detent member 35 engages in the indents in the disk 33 which correspond to the angular positions of the dial 17 in which the designations "A", "B", and "C" are in register with the apertures 22 and 23, now co-incident. The circuit conditions now prevailing will be such that the electrical system will be responsive to carrier frequency energy at a selected one of the three frequencies transmitted over the power lines 80. The condenser rotor plates 7, 8, 9, and 10 can now be adjusted by the manual control knob 15 from one angular position to another as predetermined by the detent member 35 co-operating with the peripheral indents of the clicker disk 34. For wired radio reception the space radio filter reception circuits are electrically ineffective, while for space radio reception the wired radio or carrier frequency reception circuits will be electrically ineffective.

It will be apparent that the knob 24 can be turned to either of two positions for space radio or wired radio reception. For space radio reception the masking plate 20 will be moved into a position such that the radial designations on the plate 17 will be in view as the knob 15 is rotated by contiguous increments for selection of any desired space radio program as determined by movement of the variable condensers connected with the space radio reception circuits. For wired radio reception the masking plate 20 will be in a position such that the designations "A", "B", and "C" will be in view at the aperture 25. These designations correspond to the predetermined angular positions of the dial 17 for the three set-

tings of the variable condensers as associated with the carrier frequency reception circuits for receiving any one of the three program modulated carrier frequencies. It will be obvious that the foregoing arrangements comprise compact and efficient radio apparatus for the reception of either wired radio or space radio signals. One of the chief advantages to be derived from my radio apparatus resides in that common tuning elements and a common audio frequency system are employed for the reception of signals transmitted through space or over wires. Although I have shown a preferred embodiment of my radio apparatus it will, of course, be understood that changes can be made therein without departing from the intended scope of my invention. I do not, therefore, desire to be limited to the foregoing except insofar as may be pointed out in the appended claims.

What I claim as new and original and desire to secure by Letters Patent of the United States is:

1. A radio receiving system comprising, a space radio energy collecting system, space radio signal reception circuits coupled to said space radio energy collecting system, wire lines for conveying carrier frequency energy, carrier frequency signal reception circuits coupled to said wire lines, space discharge tubes for amplifying signals received over said space radio signal reception circuits or over said carrier frequency signal reception circuits, adjustable condensers, mechanical means for moving said condensers, means for connecting said condensers to either said space radio receiving means or to said carrier frequency receiving means, a dial having two different groups of indicia thereon, said dial being mechanically connected with said condensers, and masking means for rendering said groups of indicia visible one at a time.

2. A radio receiving system in accordance with claim 1 including switches for connecting said space radio signal reception circuits to said condensers, other switches for connecting said carrier frequency signal reception circuits to said condensers, and common mechanical means for actuating said switches and said masking means.

3. A radio receiving system comprising, a space radio energy collecting system, space radio signal reception circuits coupled to said space radio energy collecting system, wire lines for conveying carrier frequency energy, carrier frequency signal reception circuits coupled to said wire lines, space discharge tubes for amplifying signals received over said space radio signal reception circuits or over said carrier frequency signal reception circuits, adjustable condensers, clicker means for predetermined the extent of the required movements of said condensers for reception of said carrier frequency signals at each of several predetermined frequencies, switches for connecting said space radio signal reception circuits to said condensers, other switches for connecting said carrier frequency signal reception circuits to said condensers, a dial mechanically connected with said condensers and having different groups of indicia thereon one of which is for carrier frequency signal reception and the other of which is for space radio signal reception, masking means for rendering said groups of indicia visible one at a time, and common mechanical means for operating said masking means, for operating said switches, and for controlling said clicker means.

ARTHUR M. TROGNER.
